United States Patent Office

Des. 222,918

Patented Feb. 1, 1972

222,918

MODEL RACING CAR

Gianpaolo Dallara, Modena, Italy, assignor to Frank Williams (Racing Cars) Limited, Slough, England

Filed Oct. 1, 1970, Ser. No. 25,291

Claims priority, application Great Britain Apr. 7, 1970

Term of patent 7 years

Int. Cl. D21—01

U.S. Cl. D34—15

FIG. 3

FIG. 4

FIG. 1 is a top plan view of the model racing car showing my new design;

FIG. 2 is a front elevational view thereof;

FIG. 3 is a front elevational view; the right side being substantially a mirror image thereof; and

FIG. 4 is a rear elevational view thereof.

I claim:

The ornamental design for a model racing car, as shown and described.
